UNITED STATES PATENT OFFICE.

ABEL H. FROST AND FRED L. BRYANT, OF CHICAGO, ILLINOIS.

MATTRESS-MAKING MACHINE.

SPECIFICATION forming part of Letters Patent No. 443,673, dated December 30, 1890.

Application filed July 26, 1890. Serial No. 359,991. (No model.)

To all whom it may concern:

Be it known that we, ABEL H. FROST and FRED L. BRYANT, of Chicago, in the county of Cook and State of Illinois, have invented 5 certain new and useful Improvements in Mattress-Making Machines; and we do hereby declare that the following is a full, clear, and exact description thereof, reference being had to the accompanying drawings, and to the 10 letters of reference marked thereon, which form a part of this specification.

This invention relates to improvements in wire-coiling machines adapted to automatically weave coiled-wire fabric for bed-bottoms. Heretofore machines for this purpose have embraced a table upon which the fabric lies while being made and a coiling-machine arranged at one end of said table and run by hand or other power. Before the end of the 15 wire strand is thrust forward into a marginal coil of the fabric being woven the said fabric has been moved longitudinally toward or from the coiler about half the width of a coil in order to insure the entrance in the said 20 marginal coil of the end of the strand of which a new coil of the fabric is about to be made. When each coil has been completed, the fabric has been moved bodily across the machine a distance equal to about half the length 25 of one twist of the coil for the same purpose. These two movements have in some cases heretofore been accomplished by moving the coil by hand and in some cases by having 30 automatic mechanism for bringing the final coil or the fabric into linear position for the insertion of the next coil and for moving the final coil longitudinally after the completion 35 of the same.

In the present invention we desire to retain 40 the coiled fabric upon the table as it is being made and to move the coiling mechanism longitudinally to and from the fabric before a coil is to be formed and to also move said coiling mechanism after a coil is formed trans- 45 versely a distance equal to about one-half the diameter of the coil. In other words, the fabric is held on the machine while the coiling device or fabric-making mechanism is moved transversely and longitudinally, as required.

50 To this end as well as to the production of a cheap and durable machine the invention

consists in the devices and combination of devices hereinafter described, and more particularly pointed out in the appended claims.

In the drawings, Figure 1 is a plan view of 55 a machine embodying our invention. Fig. 2 is a side elevation of the same. Fig. 3 is an end or rear elevation of the machine. Fig. 4 is a transverse sectional view of a portion of the machine, taken upon line 4 4 of Fig. 2, 60 looking in the direction indicated by the arrows and omitting the upper portion of the machine, embracing the coiling mechanism. Fig. 5 is a sectional view on line 5 5 of Fig. 3. Fig. 6 is a section on line 6 6 of Fig. 5. 65 Fig. 7 is a plan view of one of the movable tables on which the coiling devices are supported.

The coiling mechanism, consisting of the feed-rolls and the coiling-spindle and means 70 for operating the same herein shown, are substantially the same as shown in our former patent, No. 296,551, granted April 8, 1884, and are simply here used for the purpose of illustrating the invention, as any other coiling 75 devices may be used. We do not, therefore, minutely describe these parts, but here refer to the said patent for a more complete explanation of the construction and operation of 80 said coiling mechanism.

It will subserve the purposes of this invention to state that the wire is fed into the coiling apparatus A at a and is forced out of the same over the coiler proper at a' the several parts of the coiling apparatus being mounted 85 upon a table or platen A'.

B is the frame of the machine proper, composed of the standards b, upper and lower longitudinal side beams b' b², and upper and lower end or transverse beams b³ b⁴. Sup- 90 ported upon the side beams b' by the standards b⁵ is a table B'. It is upon this table that the fabric is made and allowed to remain immovably in position as each new coil is added thereto or until the entire fabric is 95 completed. The table B' does not extend entirely to the end of the machine, as more clearly shown in Figs. 1 and 2. At the rear end of the machine and resting upon the beams b' we place the transverse tracks B³. 100 These tracks support the two carriages hereinafter to be mentioned and the table A'.

The first or lower carriage consists of two transverse beams C, united at their ends by rods or bolts c, the beams C resting upon and adapted to be moved freely upon the tracks 5 B³. The beams C, as will be noted, extend across or transverse of the tracks B³ and carry upon their upper faces runners or tracks C'. It is upon these runners or tracks C' that the upper table C² is loosely fitted and adapted 10 to move. The table A' rests upon and is secured to the upper table C².

D is a shaft supported in suitable bearings d from the frame of the machine, at the end thereof, (see Figs. 1 and 3,) carrying upon its 15 end a flanged pulley-wheel d'. Power may be transmitted to this shaft from a suitable source of supply by means of a belt passing over the pulley d'. The shaft D is provided longitudinally with a groove d². Mounted 20 loosely upon the shaft D is a spindle or sleeve D', provided with a suitable feather adapted to enter and slide in the groove d² of the shaft D, so that said spindle or sleeve will rotate with the shaft D, while at the same time 25 it may be moved longitudinally thereon between the bearings d. Secured upon one end of the sleeve D' is a flanged pulley-wheel d³, over which a belt d⁴ is trained, so as to connect a similar pulley-wheel d⁵, mounted upon 30 the coiling-table, and by which the necessary power to operate the coiling mechanism A is obtained from the shaft D. By reason of the feathered connection of the shaft D and the sleeve D' we are enabled to have the coiling 35 mechanism in operation constantly while carrying the latter to and fro across the table. It will also be noted that by reason of the belt connection d⁴ the coiling mechanism may be moved to and from the shaft D a short 40 distance without interfering with the transmission of power to the latter.

E is a shaft mounted in suitable bearings in the frame of the machine, and to which power may be supplied by any suitable means. 45 The end of the shaft projects beyond the transverse bar b⁴ and is there provided with a wheel E'. The outer face of this wheel is provided with two sets of cogs or teeth e e', the intermediate portions e² of the face being 50 smooth and free from obstruction. Secured in bearings e³ upon the end standards b of the frame is a worm or screw-threaded shaft E². Near one end of this shaft E² is a beveled wheel or pinion E³, the teeth of which are 55 adapted to engage the teeth e e' on the wheel E'.

F is an arm or bracket, the upper end of which is rigidly secured to the lower carriage by means of bolts f passing through its end and engaging one of the transverse beams C. 60 The lower end of this arm F is provided with an enlargement or block f'. Within this block f' is a cam-plate F', having a pin or stud thereon which projects through the face of the block f', to which the handle f² is secured, 65 so that the said plate F' may be rotated within the block f'. On either side of the shaft E² is a nut f³. Each nut is provided with a pin

or projection which enters a suitable slot in the disk or plate F', so that the rotation of said plate F' will move the two nuts toward 70 or away from the shaft E²—that is, into and out of engagement with said screw-threaded shaft. This is a familiar mechanical construction. Any other well-known means for securing the arm F so that it will travel 75 lengthwise of the shaft E² as the latter is rotated may be employed, if desired.

It will be obvious from the above construction that when power is applied to the shaft E, so as to rotate the same, and the bar or arm 80 F is engaged with the shaft E² by a movement of the handle f², every rotation of the wheel E' will cause the shaft E² to be rotated intermittently—that is to say, the pinion E³ will first engage, say, the teeth e of the wheel 85 E' and will be rotated until the space e² comes opposite the pinion E³, whereupon the shaft E² will remain stationary, while the wheel E' continues to rotate. Shortly thereafter the teeth e' engage the wheel E³ and 90 again the shaft E² is rotated. When the shaft E² is rotated, it works in the engaging-nuts f³, and consequently will move the arm F and the parts engaged therewith so long as the shaft E² is rotated, and as soon as the said shaft 95 ceases to rotate the arm F and the parts secured thereto remain stationary. In this manner the lower carriage and the coiling mechanism are moved across the table intermittently. The length of this travel or move- 100 ment obviously depends upon the number of teeth e e'. As here shown, the number of teeth is sufficient to cause the carriage and coiling mechanism to move forward a distance equal to about one-half the diameter of a coil. 105 Should it be desired to run two strands of wire in the same coil, one of the sets of teeth e or e' may be omitted.

To give the coiler a movement upon the lower carriage to and from the fabric the following mechanism is employed: A shaft G is mounted transverse of the machine in suitable bearings g, located upon the lower side bars b². At either end of this bar G are rigidly secured the links G', the upper ends of 115 which are enlarged to afford bearings for a spindle or connecting-bar G², which latter is rigidly secured in said upper ends of the links G'. Secured beneath the center of the table C² by the bolts g' is a yoke or bracket G³, 120 which passes over and is loosely engaged with the upper bar G². Any rotation or oscillation of the lower shaft G is transmitted to the upper bar G² by the rigidly-connected links G'. The bracket G³ is consequently given an oscillatory movement forward and back, the length of throw depending, of course, upon the oscillation given to the shaft G.

The shaft G is operated by the following mechanism: Upon the shaft E at a point inside of the cross-bar b⁴ of the frame the disk H is mounted, said disk having upon a portion of its face h a circumferential flange constituting a cam h'. Upon the shaft G is rig- 130

idly secured an arm H' , the upper end of which is adapted to engage the face h and the cam h' of the wheel H . To lessen the friction at this point we find it convenient to provide the upper end of the bar or arm H' with a friction-roller h^2 , loosely mounted over a stud h^3 secured in the end of the arm H' . A spring H^2 is interposed between the arm H' and the transverse bar b^4 . Said spring tends to draw the upper end of the bar H' at all times against the cam wheel or disk H . It will be manifest that the rotation of the wheel H will cause the upper end of the arm H' to oscillate forward and back, as the friction-wheel h^2 first engages the face h , and then rides upon the cam h' , and then drops back again to the face h of the wheel H , and also that this forward-and-backward or oscillatory motion of the upper end of the arm H' will be communicated to the upper table C^2 through the medium of the shaft G , the links G' , the bar G^2 , and the bracket G^3 . For the purpose of properly effecting this oscillatory movement of the table C^2 , which in practice is about one-half an inch in length, the said table C^2 is mounted somewhat loosely upon the tracks C' .

The coiling apparatus and the carriages upon which it is mounted travel across the machine in the direction indicated by the arrow in Fig. 1, starting nearest the pulley-wheel d' . When it is desired to return the tables and coiling apparatus to that side of the machine, the handle f^2 is operated and the nuts f^3 thereby loosened, whereupon both tables may be moved bodily across the machine, the nuts f^3 not then being engaged with the worm-shaft E^2 .

We do not desire to be limited to the specific devices herein illustrated and described for rocking intermittently the lower table C^2 , nor to the mechanism for giving the longitudinal movement to the coiling devices, inasmuch as other well-known mechanisms will readily suggest themselves to skilled mechanicians, and because the essential feature of our invention does not consist in the details of the devices herein shown.

We claim as our invention—

1. A machine for making coiled-wire fabric, comprising a frame, suitable wire-coiling devices movably mounted thereon, and suitable mechanism for automatically moving said coiling devices, after a coil of the fabric has been made, transversely of the machine into linear position for making the next coil, substantially as specified.

2. A machine for making coiled-wire fabric, comprising a frame, wire-coiling devices movably mounted thereon, and mechanism for automatically and intermittently moving the

coiling devices, after a coil of the fabric has been made, transversely of the machine into linear position for making the next coil, substantially as specified.

3. A machine for making coiled-wire fabric, 65 comprising a suitable frame, wire-coiling devices movably mounted thereon, and mechanism for automatically moving the coiling devices longitudinally of the machine toward or from the fabric after the completion of the 70 coil, substantially as and for the purpose described.

4. The combination, in a machine for making coiled-wire fabric for bed-bottoms, of a traveling carriage, mechanism for coiling the 75 wire mounted thereon, and automatic means for intermittently moving the coiling mechanism longitudinally toward and from the fabric after the completion of the coil, substantially as described. 80

5. The combination, in a machine for making coiled-wire fabric for bed-bottoms, of a traveling carriage, mechanism for coiling the wire mounted thereon, means for moving said coiling mechanism into linear position 85 for the insertion of the next coil, and mechanism for moving the coiling devices longitudinally after the completion of a coil, substantially as described, and for the purpose set forth. 90

6. An automatic machine for weaving coiled-wire fabric, embracing the following mechanism: a stationary table upon which the fabric is to be woven, coiling mechanism mounted upon a two-part table, automatic means for 95 imparting a longitudinal movement to said coiling mechanism toward or from the fabric, and automatic means for bringing the coiling mechanism into linear position for the purpose of weaving the next coil, substantially as and for the purpose described. 100

7. In a machine for making coiled-wire fabric for bed-bottoms, the combination, with a stationary table upon which the fabric is woven and movable coiling mechanism, of 105 automatic means for intermittently moving the coiling mechanism into linear position to make the next coil and automatic means for intermittently moving the said coiling mechanism longitudinally toward or from the fabric after the completion of a coil, substantially as described. 110

In testimony that we claim the foregoing as our invention we affix our signatures in presence of two witnesses.
